UNITED STATES PATENT OFFICE.

FELIX HARRIS, OF LOS ANGELES, CALIFORNIA.

BURNER.

Application filed June 20, 1921. Serial No. 479,021.

To all whom it may concern:

Be it known that I, FELIX HARRIS, a citizen of the United States, residing at Los Angeles, in the county of Los Angeles and 5 State of California, have invented new and useful Improvements in Burners, of which the following is a specification.

This invention relates to hydrocarbon burners, and has particular reference to that 10 type of burner from which is discharged in the form of sheets, two fluids such as oil and steam or air which commingle to produce a hydrocarbon mixture, as well as an intense flame.

15 More specifically stated, the burner embodies an upper and lower section between which is interposed a disc separating the sections and which disc is flattened on its opposed faces adjacent its periphery, thereby defining with the adjacent ends of the 20 burner section slits or outlet openings through which the oil and steam are sprayed, the component parts of the burner being held associated through the instrumentality 25 of a single shifting element, thus producing a construction which can be quickly and easily assembled or disassembled as the occasion requires.

One of the chief characteristics of the 30 invention resides in providing a burner of the above mentioned character, wherein the said disc can be adjusted to direct the flame at any angle with a view of preventing the flame from striking the side wall of the furnace, thereby protecting the latter.

The nature and advantages of the invention will be better understood when the following detailed description is read in connection with the accompanying drawings, 40 the invention residing in the construction, combination, and arrangement of parts as claimed.

In the drawings forming part of this application, like numerals of reference indicate similar parts in the several views and wherein:

Figure 1 is a view in elevation of the burner constructed in accordance with the invention.

50 Figure 2 is a view taken substantially at right-angle to Figure 1, showing the outlet openings of the burner.

Figure 3 is a vertical sectional view taken on line 3—3 of Figure 1.

Figure 4 is a transverse sectional view 55 taken on line 4—4 of Figure 2.

Figure 5 is a similar view taken on line 5—5 of Figure 2.

Figure 6 is a perspective view of the disc.

Figure 7 is a sectional view taken on line 7—7 of Figure 6.

Referring to the drawings in detail, the burner which is indicated generally at A, comprises an upper section 10 and a lower section 11, both of which are identical in 65 construction. Projecting from the side of each section is a hollow boss 12, which is interiorly threaded to accommodate the feed pipes 13 and 14 respectively, the former leading from a source of oil to the section 70 10, and the latter from a source of steam to the section 11 of the burner. Each of these sections is formed with a centrally disposed hollow boss 15, which are arranged in axial alignment when the burner sections 75 are operatively associated.

The sections 10 and 11 are spaced by means of a disc 16 which is interposed between the sections as clearly illustrated in Figure 3, and the opposed faces of the disc 80 80 are formed with channels or grooves 17. The opposed faces are also recessed as at 18 and 19 respectively, these recesses extending from the channels 17 to the periphery of the disc for a purpose to be presently 85 set forth. The recess 18 is slightly deeper and yet narrower than the recess 19, these recesses defining with the adjacent ends of the section of the burner, slits or openings 20 through which the fluids above mentioned 90 are discharged from the burner. It will be noted from an inspection of Figure 2, that the disc 16 is arranged with the recess 18 adjacent the section 10 of the burner while the wider recess 19 is arranged adjacent the 95 lower section 11. Consequently, the sheet of steam emitted from the lower section 11 of the burner extends beyond the sheet of oil discharged from the section 10, so that no particle of the oil can pass beyond the 100 sheet of steam, thereby eliminating waste.

The sheet of steam mixes with the oil exteriorly of the burner in the production of a highly combustible fuel and an intense

flame, and the fuel is introduced into the fire box or furnace in the form of a spray. The upper and lower sections of the burner, together with the disc 16 are held operationally associated by means of a single fastening bolt 22 which is passed through the axially alined bosses of said sections, and also through a central opening 16' in the disc. A nut 23 is associated with the threaded extremity of the bolt as illustrated. Manifestly, the construction cannot only be assembled and disassembled in very quick order as the occasion requires, but by loosening the nut 23, the disc 16 can be adjusted, or in other words rotated to position the recesses 18 and 19 with respect to the burner sections, so that the flame may be projected in any direction, with a view of keeping the flame out of contact with the wall of the furnace. The burner in its entirety is very simple in construction and can be manufactured and sold at a very nominal cost.

While it is believed that from the foregoing description that the nature and advantages of the invention will be readily apparent, I desire to have it understood that I do not limit myself to what is herein

shown and described, and that such changes may be resorted to when desired as fall within the scope of what is claimed.

30

What I claim is:

A hydrocarbon burner comprising upper and lower tubular sections, each being open at one end, and arranged with their open ends in confronting relation, a sleeve arranged centrally within each section, the sleeves of the respective sections being disposed in axial alinement, a headed bolt passed through said sleeves and holding said sections associated, a hollow boss projecting laterally from each section and constituting an inlet therefor, a disk interposed between the open ends of said sections and having a central opening for the reception of said bolt, said disk having recesses in the upper and lower faces thereof opening at the periphery of said disk and constituting outlets for said sections, and the recess on the underside of the disk being longer than the other recess and also of a width to extend beyond the sides of the latter mentioned recess for the purpose specified.

In testimony whereof I affix my signature.
FELIX HARRIS.
